Primary Examiner — Karen Kearney*Assistant Examiner* — Katherine Holbrow(74) *Attorney, Agent, or Firm* — Cantor Colburn LLP(57) **CLAIM**

We claim, the ornamental design for a display screen or portion thereof with graphical user interface, as shown and described.

DESCRIPTION

The FIGURE is a front view of a display screen or portion thereof with graphical user interface showing our new design.

The broken lines showing the display screen and portions of the graphical user interface are included for the purpose of illustrating environmental structure and form no part of the claimed design.
